UNITED STATES PATENT OFFICE.

CHARLES H. W. KNICKREHM, OF FOREST PARK, ILLINOIS.

COMBINATION DESK AND SEAT FOR SCHOOL-ROOMS.

1,103,884.

Specification of Letters Patent. Patented July 14, 1914.

Application filed October 20, 1913. Serial No. 796,235.

To all whom it may concern:

Be it known that I, CHARLES H. W. KNICKREHM, a citizen of the United States, and a resident of the city of Forest Park, 5 county of Cook, and State of Illinois, have invented certain new and useful Improvements in Combination Desks and Seats for School-Rooms, of which the following is a specification.

10 My invention relates to school furniture and more specifically to a combination school desk and chair.

The object of my invention is the production of a combination school desk and chair 15 which will be of an adjustable nature so as to adapt the same for use in the various grades of a school or for pupils of various ages and sizes.

20 A further object is the production of a piece of school furniture as mentioned which will be of durable and economical construction and efficient in use.

Other objects will appear hereinafter.

The invention consists in the combinations and arrangements of parts hereinafter described and claimed.

25 The invention will be best understood by reference to the accompanying drawings forming a part of this specification, and in 30 which,

Figure 1 is a side elevation of a combination school desk and chair embodying my invention, a portion thereof being broken away and shown in section, Fig. 2 is a section taken on line $x-x$ of Fig. 1, Fig. 3 is a rear elevation of the device, Fig. 4 is a top plan view of the desk of the device, and Fig. 5 is an enlarged detail section taken on line $y-y$ of Fig. 4.

40 The preferred form of construction as illustrated in the drawings comprises a base 1 of hollow construction and formed preferably of sheet metal. Mounted for vertical adjustment in the base 1 are two posts 2 and 3, the post 3 being divided longitudinally into two sections 3'. Said posts 2 and 3 are releasably secured in positions of vertical adjustment by means of clamping jaws 4 and 5 respectively, there being a pair of 45 jaws coöperating with each of said posts, as clearly shown in Fig. 2. The inner ends of said jaws are pivotally secured in position by means of transversely extending pins 6, the opposite ends thereof being adapted to 50 engage against the converging opposite sides of said posts as shown. Said jaws are held

in clamping relation by means of bolts 7 and nuts 8 threaded upon said bolts which are adapted to move said jaws toward each other or into clamping relation with the 60 posts as will be readily understood. The outer ends or heads of the bolts 7 project exteriorly as shown so that the same may be engaged by a wrench or key in order to rotate the same. The nuts 8 fit square apertures formed in the adjacent wall of the base 1 whereby said nuts are held against rotation during adjustment of the bolts 7. Said posts are of hollow construction being formed preferably of sheet metal and the 70 lower end portions thereof are provided with fillers 9 preferably of wood which reinforce the same and prevent collapsing of the opposite sides thereof when the clamping jaws are moved into engagement therewith. 75

Coöperating with each of the posts is a stop block 10 held in position by means of a screw 11 which projects through an elongated slot 12 provided in the adjacent wall 80 of base 1. The blocks 10 serve as will be readily understood to hold the posts 2 and 3 in engagement with the clamping jaws, it being clear that without this provision said posts would move from engagement 85 with the inclined surfaces of the clamping jaws when the latter were moved into engagement therewith. By providing elongated slots 12, slight rotary adjustment of the members 10 is permitted in order to 90 adapt the same to conform with the positions assumed by the posts when engaged by the clamping jaws. The upper end of the base 1 is closed by plates 13 which are secured in position by thumb screws 13' which engage 95 slotted ears provided at the lateral edges of said plates, said plates preventing the entrance of dust into the base and otherwise serving to finish off the upper end thereof.

Mounted upon the upper end of the post 100 2 is a plate 14 to which is rigidly secured a seat back 15 which arises therefrom, being inclined preferably slightly rearwardly. Pivoted at 16' to the lower end of back 15 is a seat 16 adapted when in operative position to be supported upon the plate 14 as shown, said seat being adapted to be swung to vertical position when not in use in order to prevent the accumulation of dust thereon.

Mounted upon the upper end of the post 110 17 sections 3' is a desk comprising a bottom piece 17 which is secured directly as by

bolts or rivets to the upper ends of said post sections, braces 18 being employed to effect a more rigid and firm connection between said post sections and said member 17. The desk comprises also lateral walls 19 and a front wall 20 formed preferably of sheet metal, the lower ends of said walls 19 and 20 being channel formed to embrace the corresponding edges of bottom member 17 to which the same is rigidly secured through the medium of wood screws or other suitable securing devices. The top 21 of the desk is mounted for sliding movement or so as to be extended. The same is connected with the lateral walls 19 through the medium of inwardly extending angular flanges 22 provided at the upper edges of said walls which interlock with angular engaging strips 23 secured upon the under side of said top, as clearly shown in Fig. 5. The arrangement is such, as will be observed, that said top 21 will be locked to the lateral walls 19 but in such a manner as to permit of rearward sliding or extending thereof in order to adapt the desk for use with children or pupils of various ages or sizes, it being clear that with a small child the top will be moved rearwardly so as to be more readily accessible. When said top is thus moved rearwardly, a gap is formed at the forward end thereof between the same and a stationary strip 21', this gap being spanned by a strip or plate 24 of sheet metal secured upon the under side of said top projecting forwardly therefrom, as clearly shown in Figs. 1 and 4.

With a construction as set forth it will be seen that the chair or seat and the desk may be readily and easily vertically adjusted in order to accommodate children of various sizes or ages. By forming the post 3 of two independently adjustable sections 3' ready leveling of the desk is rendered possible it being clear that with this arrangement if the base is not level or is mounted upon an uneven floor the desk may be readily and quickly leveled by simply adjusting said post sections. The construction is durable and economical, and the arrangement is of neat and finished appearance.

While I have illustrated and described the preferred form of construction for carrying my invention into effect, this is capable of variation and modification without departing from the spirit of the invention. I,

therefore, do not wish to be limited to the precise details of construction set forth, but desire to avail myself of such variations and modifications as come within the scope of the appended claims.

Having described my invention what I claim as new and desire to secure by Letters Patent is:

1. A device of the kind described comprising a hollow base; a post extending into said base; a pair of clamping jaws in said base engaging said post; a rivet passing through said base and said jaws; and a bolt passing through said jaws and adapted to adjust the latter, the head of said bolt being extended from said base for manual operation thereof and the nut of said bolt being held by said base to prevent rotation thereof, substantially as described. 65

2. A device of the kind described comprising a hollow base; a post triangular in cross section extending into said base; a block in said base against one side of said post; a pair of clamping jaws in said base 80 with one end of each jaw engaging one side of said post; a rivet passing through the other end of each of said jaws and said base; and a bolt passing through said jaws and adapted to maintain the latter in operative 85 condition, substantially as described.

3. A device of the kind described comprising a hollow base having perforations therein, one of said perforations being square; a post extending into said base; a block between the inner wall of said base and said post; two clamping jaws in said base, each having one end thereof engaging one side of said post, said block and jaws coöperating to hold said post in position; a rivet extending through the other ends of said jaws and said base; a threaded bolt passing through said jaws and having its threaded end in said square perforation and its head disposed in one of the other of said 95 perforations; and a nut threaded on said bolt, disposed in and fitting said square perforation, said bolt and nut coöperating to operate said jaws, substantially as described. 100

In testimony whereof I have signed my 105 name to this specification in the presence of two subscribing witnesses.

CHARLES H. W. KNICKREHM.
